UNITED STATES PATENT OFFICE.

CHARLES H. LELAND AND HERBERT S. WEBBER, OF LOS ANGELES, CALIFORNIA.

PLURAL-CRYPT STRUCTURE.

1,093,940.

Specification of Letters Patent. Patented Apr. 21, 1914.

Application filed October 13, 1913. Serial No. 795,025.

To all whom it may concern:

Be it known that we, CHARLES H. LELAND and HERBERT S. WEBBER, both citizens of the United States of America, both residing 5 at Los Angeles, county of Los Angeles, State of California, have invented a certain new and useful Plural-Crypt Structure; and we do hereby declare the following to be a full, clear, and exact description of the invention, 10 such as will enable others skilled in the art to which it appertains to make and use the same.

This invention relates to plural crypt structure, and it may be said to consist in 15 the provision of the novel and advantageous features and in the novel and improved construction, arrangement and combination of parts and materials as will be apparent from the description and claim which follow hereinafter.

One object of the invention is to provide 20 a novel and improved plural crypt structure which is well adapted for use for burial purposes and which when so used meets in a high degree the sanitary requirements necessary to safeguard the health and comfort of 25 the public against bacterial infection or noisome odor consequent upon decomposition of bodies disposed in the crypts.

Another object of the invention is to provide 30 a novel and improved plural crypt structure in which each of the crypts is sanitary and self-contained and in which provision is made for the separate sanitation of each of the crypts.

Further objects of the invention are to 35 provide a novel and improved plural crypt structure which is simple and economical in construction, strong and durable, provided 40 with novel and effective draining means and ventilating means, in which a bed of air drying and disinfecting material is provided in each of the crypts, in which the crypts are sealed in a convenient and effective manner, 45 in which the unused crypts are completely shut off from the used crypts, and in which the marble panels at the front of the crypts are fastened in position in a convenient and effective manner.

50 Other objects and the advantages of the invention will be apparent to those skilled in the art from a consideration of the following description of the preferred form of the plural

crypt structure, taken in connection with the accompanying drawings in which—

Figure 1 is a broken longitudinal sectional view of a tier of crypts arranged within a mausoleum and having the invention applied thereto; Fig. 2 is an enlarged broken front elevational view taken on the line 2—2 of Fig. 1; Fig. 3 is an enlarged broken sectional view taken on the line 3—3 of Fig. 2; Fig. 4 is an enlarged broken sectional view taken on the line 4—4 of Fig. 2; Fig. 5 is an enlarged broken and sectional view of adjacent tiers of crypts taken on the line 5—5 of Fig. 1; Fig. 6 is an enlarged broken sectional view taken on the line 6—6 of Fig. 1; Fig. 7 is an enlarged broken sectional view taken on the line 7—7 of Fig. 6; Fig. 8 is a fragmentary view of oppositely disposed crypts showing plugs in the air inlet openings; and Fig. 9 is a fragmentary view showing the tenon at the end of the front cover for the crypt.

The crypts 10, of concrete or other suitable material, are formed in a tier or preferably a plurality of contiguous tiers and they are preferably arranged within a suitable mausoleum 11 having air inlets 12 at 80 the bottom thereof and air outlets 13 at the top thereof. The bottoms of the crypts 10 slope downwardly from front to rear and have thereon a plurality of spaced standards 14 on which may be disposed galvanized screens 15 on which burial caskets may rest; suitable air drying material 16 being disposed on the bottoms of the crypts between the standards 14.

At the rear of the tiers of crypts 10 are 90 arranged drain pipes 17 which lead to closed cisterns 18 which may have disinfecting material therein and which are preferably placed below the surface of the ground 19 under the tiers of crypts. Branch pipes 20 95 are connected to the drain pipes 17 and pass through the rear walls of the crypts and terminate at the rear of the bottom of the crypts. To prevent communication between used and unused crypts, caps 21 are screwed 100 on the branch pipes 20 of the crypts not in use and they are removed when such crypts are to be used. A subsoil drain 22 may be arranged under the mausoleum 11.

Air passageways 23 leading from below 105 to the top of the tiers of crypts are formed

in the side walls of the tiers of crypts, and the crypts 10 are provided with inlet passageways 24 in one side and with outlet passageways 25 in the other side. The passageways 24 and 25 are closed by plugs 26 when the crypts are not in use. When any one of the crypts 10 is to be used the plugs 26 may be readily removed to have the passageways 24 and 25 in open communication 10 with the passageways 23 to ventilate such crypt.

At the front thereof each of the crypts 10 is formed with a rectangular recess 27 adapted to receive the edge portions of a head or cover 28 and of a marble panel 29 which is disposed against the outer face of the head 28. The head 28 has at the sides thereof tenons 30 which are adapted to fit in corresponding mortises in the front end 20 portion of the crypt. When the crypt is to be used the head 28 may be sealed in place by means of cement or other suitable luting substance.

As seen more clearly in Fig. 2, the marble panels 29 are removably held in place by means of marble slabs 31 which are adapted to cover the edge portions of the panels 29 on adjoining crypts and have the end portions thereof beveled to fit closely together 30 so that they may be held in place by means of screws 32 which have heads 33 thereof in engagement with the ends of the slabs 31 and pass into expanding sockets 34 disposed in diverging recesses 35 formed in the front 35 portion of the crypts.

From the foregoing description it will be

seen that the plural crypt structure is comparatively simple in design and construction and that it is well adapted to carry out the objects of the invention.

While one form of construction embodying the invention has been particularly illustrated and described, many changes and modifications thereof will occur to those skilled in the art—wherefore the right is reserved to all such changes and modifications as do not depart from the spirit and scope of the invention as defined in the appended claim.

We claim:

The herein-described plural crypt structure, comprising a tier of crypts open at the front end thereof and each having air inlet and outlet passageways, said crypts each having the bottom thereof sloping downwardly from front to rear and provided with a plurality of standards and air drying material disposed between the standards, screens on the standards, removable plugs in said passageways, and means for closing the front end of the crypts.

In testimony whereof, we have signed our names to this specification in the presence of two subscribing witnesses at Los Angeles, county of Los Angeles, State of California, this 6th day of October A. D. 1913.

CHARLES H. LELAND.
HERBERT S. WEBBER.
